LABORATORY TABLE UNIT

Robert B. Morrison, North Muskegon, Mich., assignor to E. H. Sheldon & Co., Muskegon, Mich., a corporation of Michigan

Application February 12, 1954, Serial No. 28,979

Term of patent 14 years

(Cl. D16—2)

To all whom it may concern:

Be it known that I, Robert B. Morrison, a citizen of the United States, residing at North Muskegon, in the county of Muskegon and State of Michigan, have invented a new, original, and ornamental Design for a Laboratory Table Unit of which the following is a specification, reference being had to the accompanying drawings forming a part thereof.

Figure 1 is a perspective view of a laboratory table unit, showing my new design; and

Fig. 2 is an end view taken from the right side of Fig. 1.

The end not shown is substantially plain, and the other side not shown is like the side shown in Fig. 1.

I claim:

The ornamental design for a laboratory table unit, substantially as shown and described.
